UNITED STATES PATENT OFFICE.

LÉON NICOLAS BRILLOUIN, OF PARIS, AND GEORGES ARMAND BEAUV AIS, OF LYON,
FRANCE.

TELEPHONE INSTALLATION IN WIRELESS TELEGRAPHY.

1,404,573.

Specification of Letters Patent. Patented Jan. 24, 1922.

Application filed June 13, 1917. Serial No. 174,633.

To all whom it may concern:

Be it known that we, LÉON NICOLAS BRILLOUIN and GEORGES ARMAND BEAUV AIS, both citizens of the French Republic, residing the first one at Paris, France, and the second one at Lyon, France, have invented certain new and useful Improvements in Telephone Installations in Wireless Telegraphy, (for which I have filed applications in France, March 27, 1916, and November 7, 1916; Belgium, February 2, 1917; Italy, February 6, 1917; Great Britain, February 22, 1917, and Russia, March 24, April 6, 1917,) of which the following is a specification.

This invention relates to telephone installations, particularly for wireless telegraphy.

The invention has for its object to make it possible to arrange at the receiver stations a number of special electron tubes comprising a filament heated by an electric current, and two electrodes, the electron tubes being intended to act as an improved amplifier and the connection of the said electron tubes being moreover made more simply than hitherto.

The invention consists chiefly in using as an amplifier at the receiver stations of the installations of the kind in question, a certain number of special electron tubes comprising a filament heated by an electric current, and two different electrodes, and whilst connecting the second electrode of an electron tube to the first electrode of the next electron tube, and the first electrode of the first lamp to the line, the second electrode of each electron tube being moreover connected through a resistance to one of the poles of a source of current—in inserting a condenser into each of the connections of the electrodes with each other.

Apart from this main arrangement, the invention comprises other arrangements more fully described in the following.

The invention will be understood from the following description and the accompanying drawings given by way of example.

The improvements are mainly intended to be used in a system simultaneously as an amplifier and detector and in which case the receiver terminals are connected to the receiving set of a wireless telegraph installation. The improvements may be used also in a system as an amplifier only to amplify any impulses that may be imposed upon the

receiver terminals and then may be included in wireless telegraphy installations with a detector. It may be used in a further application thereof as an amplifier on telephone installations and the receiver terminals respectively connected to the two lines conducting the current from the transmitting station to the receiving station.

Fig. 1 is a diagrammatic view of receiver stations and telephone installation embodying the features of the invention.

Fig. 2 is a similar view showing a modified structure.

Fig. 3 is a similar view showing a still further modified structure.

Figure 4 is a diagrammatic view illustrating an explanatory curve of working.

Figure 5 illustrates an installation similar to that shown in Figure 1 but showing another modification.

A certain number of special electron tubes $a^1 a^2 a^3$ are taken, each comprising a filament $a^{10} a^{20} a^{30}$ which can be heated by a source of electricity, a first electrode $a^{100} a^{200} a^{300}$ next to the filament, having for instance the shape of a grid (electrode hereinafter referred to by the name of "grid") and a second electrode $a^{1000} a^{2000} a^{3000}$ separated from the filament by the grid and constituted for instance by a cylinder or by a plate (this electrode being hereinafter referred to by the name of "plate".)

The property is utilized which such electron tubes possess, that is to say, if to the grid is applied a variable tension v and to the plate a constant tension V , there will pass from the hot filament to the two electrodes, electronic currents of respective intensities i and I which vary with the variable tension v .

A source of electricity b (storage or primary batteries) is taken, intended to supply current for heating the filaments a^{10}, a^{20}, a^{30} of the lamps a^1, a^2, a^3 , and the said filaments are connected to the terminals of the said source of electricity, the connection being made in parallel.

Another source of electricity c is taken, intended to produce the tension v in the plates $a^{1000}, a^{2000}, a^{3000}$. One of the terminals of the said source c is connected to the terminal of opposite polarity of the source of electricity b , and the plates $a^{1000}, a^{2000}, a^{3000}$ are connected to the other pole of the said source of electricity c , a resistance d^1, d^2

being inserted between each of the said plates and the source c .

One of the receiver terminals e^1 of the installation is connected to that of the poles 5 of the source b , which is connected to the source c , and the other receiver terminal e^2 to the grid a^{100} of the first electron tube, a condenser f^1 being preferably inserted between the said terminal and the said grid.

10 These receivers are of the kind hereinbefore explained. In the particular application of the improvements just explained a wireless telegraphic installation without a detector is considered, and the improved device operates 15 both as a detector and amplifier.

The plate a^{1000} of the first electron tube is connected to the grid a^{200} of the second electron tube, a condenser f^2 being inserted between the said plate and grid. Identical connections are made between the plates and 20 grids of the next electron tubes.

Finally, the resistance that was to be inserted between the plate a^{3000} of the last electron tube and the source of electricity c , is 25 replaced by a telephone apparatus g .

In this way an installation is obtained in which, provided that the tension of the plates relatively to that of the corresponding filaments be such that electronic currents (which 30 can pass only from the negative to the positive) can pass from the said filaments to the said plates, an amplifying effect is produced from one electron tube to the next one.

In fact, in case of an increase of voltage of 35 the grid a^{100} produced by an emission of current into the line (in the case of ordinary telephony) or by a reception of waves (in the case of wireless telegraphy) and transmitted to the grid a^{100} , if necessary through 40 the condenser f^1 , the intensity of the current passing in the plate a^{1000} is also increased, and this in such a manner that the variation of voltage in the plate will be considerably greater than the variation of voltage in 45 the grid. It may be noted that this variation of voltage in the plate is of opposite sign with respect to the variation of the voltage in the grid. In fact, the increase of voltage in the grid coming from an outside source 50 which renders such grid more positive, will cause a certain number of electrons to be attracted to and retained by the plate, because of its high positive potential. It is known that these particles give a negative 55 charge to a neutral plate and will consequently render the plate less positive, i. e., diminish its positive potential. The electronic current which lessens the potential of the plate will then be neutralized by a current 60 flowing from the battery into the plate. This effect can be foreseen by a simple consideration of Ohm's law. On the one hand, as soon as an electronic action is established, a current is established in the plate to neutralize 65 the electronic current, but at this moment

there exists a drop of potential due to the resistance d' inserted between the battery and the plate a^{1000} . On the other hand, the electronic current increases with an increase of potential of the grid. The increase of voltage in the grid thus produces a decrease of the voltage in the plate. The resistance d' should have a zero value in order that the potential in the plate may remain unaffected. This results in a corresponding variation of 70 the voltage and of the current passing through the grid a^{200} , and in a still greater variation of the voltage and of the intensity of the current passing through the plate a^{200} and so on, these variations being now negative and now positive, and generally speaking, alternately negative and positive, because, owing to the existence of the resistances d , to each increase of current in one plate will correspond in the same plate a 80 proportional fall of potential.

In order that the transmission of variations of voltage of a plate to the next grid may take place while the mean voltage of the grid is maintained at a suitable value near 90 that of the voltage of the filament, a condenser is inserted between the plate and the grid, owing to which the variations of voltage are transmitted without the average voltage of the different grids being transmitted. 95 With this end in view, each grid is connected by means of a resistance h^1 h^2 h^3 to a potentiometer j connected across the terminals of a source of current k , one of the terminals of which is connected to the positive terminal of the source of current b , owing to which the mean voltage of the grid can be fixed at a suitable value. It will be understood from the immediately foregoing conditions that the resistances d are not eliminated, but, on the contrary, are embodied in the organization as hereinbefore explained. 100

In telephone installations, or in wireless telegraphy installations, wherein it is unnecessary to rectify the current, the potentiometer will have to be preferably adjusted so that the grid has a mean negative voltage 105 relatively to the whole of the filament, in order to avoid any current passing into the grid.

But as in wireless telegraphy it is indispensable to have a current rectifier, it is possible to combine the amplifier with the current rectifier, to render it possible to detect 110 the mean current.

In this case, the adjustment of the potentiometer must be such as to maintain the mean voltage of each grid at a positive value relatively to the whole of the corresponding filament, an absolutely essential condition 115 for obtaining rectification of the current.

An examination of the curve A A¹ (Figure 7) indicating variations of intensity i of the electronic currents arriving at the grid, as a function of the potential v of the grid, will 120

in fact show that this curve has a very pronounced curvature in one portion corresponding to a positive voltage greater than the voltage of the filament.

- 5 The curve D D¹ shows the variation of the intensity I in the plate in accordance with the variation of the voltage v of the grid, the voltage of the plate being supposed to remain constant. Fig. 4 also shows another 10 curve C C¹ which is obtained as follows: It is supposed that the grid has a mean voltage v but that the said voltage is subjected to sinusoidal variations with respect to the said mean voltage v and that the said variations have a constant frequency and a constant amplitude and the current i is the mean current of the grid. The curve C C¹ will coincide with the curve A A¹ when the latter assumes a straight line but will differ there- 15 from by reason of the curvature of the said first-mentioned curve. In fact then the variations of the potential (around the mean potential) will produce instantaneous variations of intensity in the current of the grid 20 and the positive variations will be stronger than the negative ones in consequence of the curvature. This results in an increase in the mean intensity and the curve C C¹ passes over the curve A A¹. If it is supposed that 25 the grid is connected through a resistance h (having a value r) to a point having a voltage v^1 (point B¹ of Fig. 4) the true voltage of the grid will be given: first, if there are not continuous waves, by the point a where 30 the curve A A¹ intersects with the line B B¹ (line given by the equation $v = v^1 - i r$); second, if continuous waves are sent in the grid by the point of intersection of the curve C C¹ with the line B B¹. The presence of sus- 35 tained waves produces a variation of the mean voltage of the grid and the said variation produces itself a variation of the current I of the plate, which latter variation is a continuous one and can be detected in the 40 telephone.

The conditions of best sensitiveness require such an adjustment of the potential v' at the point of connection of the resistance h to the potentiometer, that the straight line 45 B B¹ intersects the curves A A¹ and C C¹ at two points at a distance from each other, and also such a construction of the electron tubes and such an adjustment of the potential V of the plate assured by the source of current c , and of the heating of the filament, that the curve D D¹ increases as quickly as possible with the potential of the grid.

In the case of wireless telegraphy, it is generally speaking advisable moreover to 50 choose the capacities f^2 f^3 of as small values as possible, in order that only the high frequency is transmitted from one electron tube to the next, the low frequency being stopped.

The amplifier-detector thus connected, constitutes a filter which greatly reduces the

secondary currents and the injurious strong transmissions, and strengthens only very weak transmissions. This result has been proved as correct by practice. This effect is in fact always obtained in wireless telegraphy when use is made of a high frequency amplifier instead of a low frequency amplifier.

More particularly, it has been found possible to do away completely with the permanent noise which is emitted by most amplifiers and which is due to irregularities of the electronic current of the first electron tube, amplified by the next electron tubes.

The installation could be very advantageously completed by certain auxiliary connections having for their object to increase the amplifying, the said auxiliary connections could be moreover applied equally to any installations comprising amplifiers provided with the special electron tubes mentioned above, whatever be the method of connecting the said electron tubes.

For instance, as shown in Figure 2, it would be possible to use capacities b^1 b^2 connecting the plate of one electron tube to the grid of one of the preceding lamps. Thus the same transmission is caused to pass twice through one electron tube, and the amplifying is modified. More particularly, a capacity s (Figure 5) between the grid and the plate of one and the same electron tube renders it possible to reduce the amplification and even to suppress the amplifying for a frequency exceeding a given limit as shown by Fig. 5 at s , the remaining part of this diagram being similar to the organization hereinbefore described.

In the case where the reception takes place in a resonant circuit, and more particularly in the case of wireless telegraphy, it may be advisable, whatever be the type of amplifier with special electron tubes, amplifying the oscillations received, to connect that of the

terminals e^2 of the condenser of the oscillating circuit of reception, which is not connected to the installation and is merely connected to the grid a^{100} , to the plate of one of the electron tubes, the voltage of which undergoes an increase when the voltage of the grid a^{100} increases (generally plate of an electron tube of even series) in the case of the amplifier (shown in Figure 1), and this either by an adjustable capacity, or even by a resistance. The same result can be moreover obtained by the usual connections, owing to the unavoidable capacity existing between the connection wires. By "even series" is meant the second, fourth, sixth, etc., electron tubes of the amplifier, and by the term "odd series", is meant the first, third, fifth, etc., electron tubes of the amplifier, the first electron tube being that nearest to the terminals e^1 and e^2 .

In that way is obtained a reaction, on the oscillating circuit of the receiving set, of oscillations amplified by the apparatus, and in that way it becomes possible to maintain regular electric oscillation in the oscillating circuit.

In order to limit this effect or to do away with it, the said terminal e^2 could be connected by another variable capacity or resistance to the plate of an electron tube in which the voltage decreases when the voltage of the grid a^{100} increases (generally plate of an electron tube of odd series).

These two connections can be preferably made or broken at will by means of variable capacities. Mechanical arrangements easy to design will make it possible to control these two reactions by a single movement.

For example, as shown in Figure 3, it would be possible to use a condenser q having two fixed electrodes q^1 , q^2 , each connected by means of an adjustable resistance r^1 , r^2 , to a variable point of the resistance d , of two different electron tubes a , and also, a movable electrode q^3 connected to the terminal e^2 and brought at will opposite one or the other of the fixed electrodes.

It is thus that continuous and gradual regulations can be arranged for, making it possible to bring the system very near to the state where the oscillations produced come into step or the regulation of the apparatus is such that it begins to heterodyne, which state corresponds to a very strong amplifying.

In this way, by production of oscillations maintained in the reception circuit, it is possible to receive directly, by interference without it being necessary to use an auxiliary heterodyne, waves emitted by any wireless telegraphy station with sustained waves and to receive with a very great amplification emissions from stations with damped oscillations or waves.

Finally, if the regulation is effected near the limit of coming into step of oscillations in the circuit, there will be received, in the absence of these oscillations and with their natural sound but very strongly amplified, the waves emitted by stations with damped waves.

It should be noted that, in order to obtain a regular working, it is advantageous to use the following arrangements:

Such a construction of the resistances that their self-inductance and capacity is entirely negligible, for which reason they are preferably made from a very short high resistance wire, for instance by means of a very thin deposit of metal on an insulating support or on carbon.

It is useful to limit the length of the connection wires.

The source of current of the apparatus may advantageously be connected to any

metal parts comprising elements of the installation such, for example, as buttons, hinges, squares, bolts and the metal springs of the telephone operator helmet.

Obviously the invention is not limited to the methods particularly indicated, but comprises on the contrary any modifications within the scope of the claims.

Having now particularly described and ascertained the nature of our said invention and in what manner the same is to be performed, we declare that what we claim is:

1. A receiver station for installations of the classes specified having a number of electron tubes, each electron tube being provided with a filament heated by an electric current furnished by a first source of current and two different electrodes, one of which is connected through a resistance, for the first electron tubes and through a receiving apparatus, for the last electron-tube, to a second source of current of given voltage, the other electrode being connected to a potentiometer through a resistance and being, also, connected by a condenser, for the first electron tube, to one of the terminals of the receiving station and, for the other electron tube, to the plate of the preceding electron tube; the plate of one electron tube being connected by a capacity to the grid of one of the preceding electron tubes.

2. A receiver station for installations of the classes specified, having a number of electron tubes, each electron tube being provided with a filament heated by an electric current furnished by a first source of current and two different electrodes, one of which is connected through a resistance, for the first electron tubes, and through a receiving apparatus, for the last electron tube, to a second source of current of given voltage connected to the terminal of opposite polarity of the first source of current, the other electrode being connected to a potentiometer through a resistance and being also connected by a condenser, for the first electron tube, to one of the terminals of the receiving station and, for the other electron tubes, to the plate of the preceding electron tube, the terminal of the receiving station, which is not connected to the grid of the first electron tube, being connected to that of the poles of the first source which is connected to the second.

3. A receiver station for installations of the classes specified, having a number of electron tubes, each electron tube being provided with a filament heated by an electric current furnished by a first source of current and two different electrodes, one of which is connected through a resistance to a second source of current of given voltage, the other electrode being connected to a potentiometer one of the terminals of which is connected to the positive terminal of the

first source of current through a resistance and being, also, connected by a condenser, for the first electron tube, to one of the terminals of the receiving station and, for the 5 other electron tubes, to the plate of the preceding electron tube and the filaments of each electron tube being connected in parallel to the terminals of the first source of current.

10 4. A receiver station for installations of the classes specified, having a number of electron tubes, each electron tube being provided with a filament heated by an electric current furnished by a first source of current and 15 two different electrodes, one of which is connected through a resistance, for the first electron tubes, and through a receiving ap-

paratus, for the last electron tube, to a second source of current of given voltage, the other electrode being connected to a potentiometer 20 through a resistance and being also connected by a condenser, for the first electron tube, to one of the terminals of the receiving station and, for the other electron tubes, to the plate of the preceding electron tube. 25

In testimony whereof we have hereunto set our hands in presence of two subscribing witnesses.
